DESIGN FOR A BILLFOLD

Corry T. Meeker, Joplin, Mo.

Application March 14, 1936, Serial No. 61,635

Term of patent 3½ years

To all whom it may concern:

Be it known that I, Corry T. Meeker, a citizen of the United States, residing at Joplin, in the county of Jasper and State of Missouri, have invented a new, original, and ornamental Design for a Billfold, of which the following is a specification, reference being had to the accompanying drawing, forming a part thereof:

The figure is a perspective view of a billfold showing my new design.

The design appears wholly on that face of the

billfold shown, the opposite side of the billfold being plain.

The linings for colors on defined surfaces indicate that certain adjacent surfaces are of contrasting colors. The colors extend entirely over the surfaces on which they are partially indicated.

I claim:

The ornamental design for a billfold substantially as shown and described.

CORRY T. MEEKER.
